COLUMBIA PLANOGRAPH CO., WASHINGTON, D. C.

UNITED STATES PATENT OFFICE.

WALTER P. WHITAKER, OF MISSOULA, MONTANA.

WRENCH.

1,159,631.

Specification of Letters Patent.

Patented Nov. 9, 1915.

Application filed June 21, 1915. Serial No. 35,385.

To all whom it may concern:

Be it known that I, WALTER P. WHITAKER, a citizen of the United States, residing at Missoula, in the county of Missoula, State of Montana, have invented certain new and useful Improvements in Wrenches; and I do hereby declare the following to be a full, clear, and exact description of the invention, such as will enable others skilled in the art to which it appertains to make and use the same.

This invention relates to improvements in wrenches.

One object of the invention is to provide a sliding jaw wrench which is automatic in its nature.

Another object is to provide a sliding jaw wrench which is positive in its gripping action on a piece of work and which will return to normal position when released from the work.

Other objects and advantages will be apparent from the following description when taken in connection with the accompanying drawing.

In the drawing: Figure 1 is an elevation of a wrench made in accordance with my invention. Fig. 2 is an edge view, Fig. 3 is a longitudinal sectional view on the line 3—3 of Fig. 2. Fig. 4 is a section on the line 4—4 of Fig. 1. Fig. 5 is a longitudinal section on the same line as Fig. 3, but showing the movable jaw and extension in elevation, and Fig. 6 is a perspective view of the removable jaw, removed.

Referring particularly to the accompanying drawing, 10 represents the shank of the wrench which has formed on one end a head 11 provided with a stationary jaw member 12 and having formed transversely thereof a slot 13 which widens toward an edge of the wrench inwardly of the outer face of the stationary jaw. Within this slot is a substantially triangular plate 14 on the smaller end of which is formed a jaw 15 which slides toward and away from the stationary jaw 12 as will be understood. Likewise within the slot 13 and connected at one end to the plate 14 and at its other end to the head is a coil spring 16, this spring normally drawing the jaw 15, to the outermost limit of its movement away from the jaw 12. Formed longitudinally through the shank is a channel 17 in which is disposed a rod 18, one end being beveled and bearing against the adjacent inclined edge of the

plate 14. The handle of the wrench which is carried by the other end of the shank is divided into a stationary part 19 and a movable part 20 pivotally connected to the shank 60 and held in close relation to the portion 19.

The portion 19 has a groove 22 which receives the rib 23 carried by the section 20 of the handle. On the inner end of the rib is a projection 24 which engages with the 65 adjacent end of the rod 18.

In normal position, the arm 15 is in position away from the arm 12 and the member 20 extending outwardly at an angle from the shank. The jaws are thus in position to straddle a piece of work which is of a size equal to the distance between the jaws. By swinging the member 20 inwardly toward the member 19 the projection 24 will engage with the end of the rod 75 18 and force the same outwardly so that its beveled end will engage the inclined edge of the plate 14 and force the jaw 15 against the arm 12 and firmly clamp the work between the jaws. The mutually adjacent 80 faces of the jaws are ribbed, as shown at 25, to be received in the grooves of the toothed plates 26 for engagement with round work such as pipes, said toothed plates being secured in place by the set screws 27. 85

What is claimed is:

1. A wrench comprising a shank having a longitudinal bore formed therethrough, a stationary jaw member formed on one end of the shank and having an outwardly 90 widening channel formed therethrough, a movable jaw carrying an extension of the same size and shape as the said opening and disposed therein, a rod slidable through the bore of the shank and having a beveled end 95 engaging with the adjacent inclined edge face of the said extension, means for holding the movable jaw remote from the stationary jaw, and means carried by the other end of the shank for sliding the rod in the 100 bore to move the movable jaw toward the stationary jaw.

2. A wrench including a shank having a longitudinal bore and a rod slidable therethrough and provided with a beveled end, 105 a stationary jaw and a movable jaw carried by one end of the shank, an approximately triangular member carried by the movable jaw and slidable under the stationary jaw, the beveled end of the rod engaging with 110 one of the inclined edge faces of the triangular member, a spring connected to the

shank and to the movable jaw for holding the movable jaw away from the stationary jaw and a pivoted hand grip carried by the other end of the shank and provided with 5 means for engagement with the adjacent end of the rod to move the rod longitudinally in the bore whereby the beveled end of the rod will engage with the said edge face of the

triangular member and move the movable jaw toward the stationary jaw.

16 In testimony whereof, I affix my signature, in the presence of two witnesses.

WALTER P. WHITAKER.

Witnesses:

J. CLARENCE KEENAN,
FREDERICK C. WEBSTER.
